(57) **CLAIM**

The ornamental design for a soft goods animal as shown and described.

DESCRIPTION

FIG. 1 is a front view of a soft goods animal;

FIG. 2 is a rear view of the soft goods animal of FIG. 1; FIG. 3 is a first side view of the soft goods animal of FIG. 1;

FIG. 4 is a second side view of the soft goods animal of FIG. 1;

FIG. 5 is a top view of the soft goods animal of FIG. 1; and, FIG. 6 is a bottom view of the soft goods animal of FIG. 1. The stippling in the figures represents a contrast in appearance. The broken lines depict the bounds of the claimed design and form no part of the claimed design.

1 Claim, 6 Drawing Sheets
